DESIGN FOR A DIAPHRAGM MOTOR VALVE

William H. Vogt, Rochester, N. Y., assignor to
Taylor Instrument Companies, Rochester, N. Y.,
a corporation of New York

Application January 29, 1936, Serial No. 60,877

Term of patent 14 years

To all whom it may concern:

Be it known that I, William H. Vogt, a citizen of the United States of America, residing at Rochester, in the county of Monroe, State of New York, have invented a new, original, and ornamental Design for a Diaphragm Motor Valve, of which the following is a specification, reference being had to the accompanying drawing, forming a part thereof, wherein:

Fig. 1 is a perspective view of a diaphragm

motor valve, a cover portion being shown detached; and Fig. 2 is a plan view of the top thereof removed, showing my new design.

I claim:

The ornamental design for a diaphragm motor valve, as shown.

Signed at Rochester, New York, this 28th day of January, 1936.

WILLIAM H. VOGT.
